(57) **CLAIM**

The ornamental design for a bag strap connector, as shown and described.

DESCRIPTION

FIG. 1 is a front perspective view of the first embodiment of a bag strap connector;

FIG. 2 is a rear perspective view of the bag strap connector of FIG. 1;

FIG. 3 is a front elevational view of the bag strap connector of FIG. 1;

FIG. 4 is a rear elevational view of the bag strap connector of FIG. 1;

FIG. 5 is a top view of the bag strap connector of FIG. 1;

FIG. 6 is a bottom view of the bag strap connector of FIG. 1;

FIG. 7 is a left side view of the bag strap connector of FIG. 1;

FIG. 8 is a right side view of the bag strap connector of FIG. 1;

FIG. 9 is a front perspective view of a second embodiment of the bag strap connector shown in FIG. 1;

FIG. 10 is a rear perspective view of the bag strap connector of FIG. 9;

FIG. 11 is a front elevational view of the bag strap connector of FIG. 9;

FIG. 12 is a rear elevational view of the bag strap connector of FIG. 9;

FIG. 13 is a top view of the bag strap connector of FIG. 9;

FIG. 14 is a bottom view of the bag strap connector of FIG. 9;

FIG. 15 is a left side view of the bag strap connector of FIG. 9; and,

FIG. 16 is a right side view of the bag strap connector of FIG. 9.

The broken line showing is included for the purpose of illustrating unclaimed subject matter and forms no part of the claimed design.
